VIBRATORY DRIVE APPARATUS

Thomas Hubbard Morgan, Kittanning, Pa., assignor to S. S. Bruce and H. C. Oliver, both of Pittsburgh, Pa., and T. Hubbard Morgan, Kittanning, Pa., trustees

Application June 26, 1940, Serial No. 342,498

3 Claims. (Cl. 60—54.5)

This invention relates to vibratory drive apparatus, and more particularly to apparatus of the character stated for imparting synchronous vibration to a plurality of vibratory units.

It is sometimes desirable to vibrate a series of devices or to apply vibration at more than one point to a single device, and to apply such multiple vibratory forces in synchronism, as for example, in the conveyance of materials, and also in the separation of materials such as ores, minerals, grains and other substances.

Among the objects of the present invention are, to provide an apparatus for the synchronous vibration of a plurality of vibratory units; to provide apparatus wherein high frequency pneumatic vibrations are converted and distributed through hydraulic means to a multiplicity of vibratory units for synchronous vibration thereof; and to provide for the application of the vibratory force equally to each of the plurality of vibratory units through positive action of the hydraulic distribution of said force.

My invention also contemplates means to provide against time lag in the hydraulic distribution of the vibratory force to the several vibratory units; means to provide for starting the multiple system under load; and to provide apparatus which is simple, economical and highly efficient.

Additional objects and advantages will become apparent from the following description taken in connection with the accompanying drawings, wherein:

Fig. 1 is a diagrammatic view of an application of the vibratory drive embodying my invention;

Figs. 2 and 3 are diagrammatic views illustrating other devices equipped with a plurality of vibratory units for vibration thereof by my invention;

Fig. 4 is a plan view of the master drive; and

Fig. 5 is a side elevation thereof, partly in section, Figs. 4 and 5 being connected diagrammatically by the system of piping or fluid lines employed, in order to facilitate illustration of the fluid circulation.

Referring to Figs. 4 and 5 of the drawings, a master vibratory drive unit is preferably mounted in a suitable frame or support including a horizontal bed 2 shown in the form of a channel supported at its ends by uprights 3. 4 designates angle brackets slidably positioned on the web of the channel bed 2 and being spaced apart to receive and support a master vibrator V therebetween, said vibrator being fixed to the members 4 by the heads or end plates 5 thereof.

The vibrator V is preferably of the reciprocating piston type, as for example, the high frequency pneumatic vibrator shown in my prior United States Patents Nos. 2,119,235 and 2,196,224. Such a vibrator readily lends itself to external connection with means to be vibrated as by connection with the piston or cylinder thereof.

Referring generally to the vibrator V, 6 designates the cylinder and 7 the piston therein, the latter having a piston rod 8 extending beyond one end of the cylinder through a packing gland 9. Air or other fluid under pressure is admitted to the cylinder 6 through a connection 10 for operating the vibrator.

15 In the embodiment of my invention as illustrated, the outer terminal end of piston rod 8 is secured centrally of and to a transverse horizontal drive bar 11. In this embodiment, 12 designates a plurality of hydraulic cylinders having pistons 13, the piston rods 14 thereof extending in parallel relation toward and being attached at 15 to the drive bar 11.

20 The four hydraulic cylinders 12 illustrated, are in horizontal series spaced in balanced relation on either side of the vibrator piston rod 8 for equal reciprocating movement of their pistons 13 by the movement of the rod 8. Each of the cylinders is anchored in fixed position to a transverse support 16, as particularly shown in Fig. 5, the support 16 being carried by the bed 2.

25 The four hydraulic cylinders 12 illustrated, are in horizontal series spaced in balanced relation on either side of the vibrator piston rod 8 for equal reciprocating movement of their pistons 13 by the movement of the rod 8. Each of the cylinders is anchored in fixed position to a transverse support 16, as particularly shown in Fig. 5, the support 16 being carried by the bed 2.

30 Each of the cylinders 12 is connected in fluid circuit with an individual vibrator unit comprising a cylinder 17 and a piston 18, by suitable conduits in such a manner that pistons 13 and 18 of their respective cylinders are continuously in contact with pairs of fluid columns designated by their respective conduits 19 and 20 containing a suitable fluid, as for example, a light turbine oil.

35 Cylinders 12 and 17 are each ported on either side of the normal range of piston travel therein so that each fluid column 19 extends between an end of each piston 13 and 18, and each other fluid column 20 extends between the other ends of said pistons, thus providing a complete series fluid circuit for movement in either direction of fluid and pistons.

40 In other words, the fluid columns 19 and 20 act as connecting links between the pistons of respective pairs of cylinders 12 and 17, whereby a movement imparted to one piston positively moves the other in either direction of reciprocating movement.

45 50 55 As shown in Fig. 1, pairs of cylinders 17 are

connected to members 21 and have their pistons 18 connected by their piston rods to parallel members 22, the members 21 and 22 diagrammatically indicating pairs of members for supporting the respective decks or frames of a double deck material separator or screen as more particularly shown in detail in my copending application, Serial No. 342,497, now Patent 2,285,348.

A screen or other device may be supported by the members 21 and another by the members 22, said members and screens being suspended in any suitable manner for vibration thereof by the series of units 17-18.

Thus it will be understood that upon operating the master vibrator V, its piston 7 will vibrate the drive bar 11 with a reciprocating movement, which vibrations are transmitted to the fluid columns 19 and 20 through hydraulic units 12-13, the vibratory force of the vibrator V being distributed and imparted equally to the several vibrator units 17-18 for vibrating the screen, separator or other device. Since the pistons 18 are connected to one member of unit and the cylinders 17 to another in Fig. 1, the applied vibrations will be directly imparted to the units to vibrate the same in opposite directions.

The drive bar 11 is preferably of sufficient strength as a beam to resist variations which may occur due to load changes at the various separate vibrator units 17-18. Should abnormal conditions occur, such as the complete overloading of one unit 17-18, the force of vibrator V will nevertheless be applied to the fluid columns 19 and 20 to said unit, and since its load is immovable, the drive bar will bend and indicate the necessity for shutting down the apparatus to remedy the difficulty. In this connection, the drive bar 11 is preferably of lesser strength in bending than the piston rod 3 to prevent injury to the latter.

In order that the vibrations of the several units 17-18 may be absolutely equal in magnitude and operate in synchronism, it is important that the conduits or lines carrying the fluid columns 19 be substantially equal in length, and that the columns 20 should have substantially equal lengths, thereby eliminating any time lag in the hydraulic circuit to any one of the units 17-18, which might otherwise be caused by unequal amounts of friction in unequal lines.

Figs. 2 and 3 illustrate the application of my invention to the vibrating conveyance of material through the use of multiple vibrator units 17-18 connected and actuated as before by the master vibrator drive. By the spaced application of synchronous vibration to a plurality of points along a conveyor surface, I am able to place long sections of conveyor in synchronous vibration for highly efficient conveyance of materials such as grain, sand, ore and other substances of a similar character.

In Fig. 2, 23 designates a tubular conveyor suspended by springs diagrammatically indicated at 24, said conveyor having attachments 25 for securing the cylinders 17 of the separate vibrator units, their pistons 18 being secured to a heavy weight or to a fixed member 26.

By driving the vibrators 17-18 by the master vibrator V, the conveyor tube 23 will be vibrated throughout in synchronism, the pistons 18 being stationary with the weight or anchorage 26, and the cylinders 17 reciprocating to vibrate the tube. Upon adjusting the units 17-18 at a proper angle, the vibrating conveyor will advance ma-

terial introduced thereto in a steady ready-flowing stream.

Fig. 3 illustrates a similar adaptation for the opposite but equal synchronous vibration of a pair of conveyor tubes 23 and 23a, as will be readily understood, the pistons 18 of the cylinders 17 being secured by attachments 25a to the conveyor tube 23a.

An important feature of my invention resides in the provision of means in connection with the master vibrator mounting to enable starting under load, as for example, when the separator or conveyor is loaded with material to be treated. In such an event, the inertia of the apparatus and load may be too great for starting with the cylinder 6 of the vibrator V fixed.

I have therefore provided an adjustable mounting for this vibrator by permitting sliding of the mounting brackets 4 on the bed 2. The supporting flanges of the brackets are slotted at 27 to receive locking studs 28 having locking hand wheels 29 for securing the vibrator V to the bed.

In addition, each bracket 4 is engaged by a spring 30 exerting a tension on the brackets in opposite directions along a common line parallel to the axis of the vibrator V, each spring 30 having an adjusting screw 31 for adjusting the spring tensions.

In starting the master vibrator, the air or other fluid is admitted to the cylinder 6 through connection 10, and locking means 28-29 are loosened to permit reciprocation of the vibrator cylinder relative to its piston through the slotted connections 27 with the bed 2, said movement of the cylinder 6 being against the tension of the springs 30. Should the load be too great, the tension of the springs may be relieved by screws 31 until the vibrator is in motion.

With the vibrator case in motion, the tension of springs 30 is next increased, thereby decreasing the amplitude of the movement of the cylinder and increasing the amplitude of the piston movement until the piston assumes the load, at which time the cylinder 6 may be locked in fixed position by the means 28-29. This variation in amplitude of movement in the piston rod 8 is effected without substantial change in frequency, and upon locking the cylinder in place, the vibrator piston and rod vibrate the drive bar 11 to motivate the multiplicity of vibratory units as described.

As shown, my master drive structure includes means for charging and maintaining the hydraulic columns 19 and 20 from a supply reservoir 32 containing a light turbine oil or other suitable fluid. 33 designates a pressure line for placing the oil or fluid in the reservoir 32 under the pressure of the main air supply line 34, said line 33 having a control valve 35. A separate line 36 feeds the vibrator V through connection 10 from the air supply 34, line 36 having a regulating valve 37 by which the vibrator operation may be controlled.

The hydraulic fluid passes from reservoir 32 through a manifold line 38, having valve 39, to a plurality of lines 40, each connecting one of the lines defining the columns 19 or 20 between cylinders 12 and 11, the lines 40 being shown as connecting with the lines defining the fluid columns 20. Each line 40 is provided with a shut-off valve 41 and a by-pass connection 42 with the lines defining fluid columns 19, whereby the columns 19 and 20 may be readily established from the pressure supply 32 and may be replen-

ished when necessary. 43 designates check valves in each line 40 to permit flow of hydraulic fluid from the reservoir 32 to the columns 19 and 28, but preventing a reverse flow therefrom to the reservoir.

From the foregoing description it will be seen that I have provided a vibration system and apparatus wherein the master pneumatic operable vibrator imparts mechanical action which is positively and synchronously converted into hydraulic action for actuating a series of separate units or vibrators in the manner and for the purposes set forth.

Various changes and modifications are contemplated within the scope of the following claims.

What I claim is:

1. A vibratory drive apparatus including a master vibrator, a plurality of hydraulic units simultaneously vibrated thereby, a plurality of remote vibratory units including cylinder piston means, hydraulic conduits connecting each of the latter units with a hydraulic unit for synchronous vibration of said remote units by the master vibrator, said conduits containing columns of fluid and having substantial equal lengths to equalize friction in said conduits and prevent time lag in any of said remote units.

2. A vibratory drive apparatus for the synchronous transmission of high frequency vibrations including a master high frequency pneumatic vibrator having a cylinder and piston, a plurality of hydraulic units comprising fixed cylinders and movable pistons, a drive bar connecting the master vibrator piston and all of the pistons of said units for simultaneously vibrat-

ing the latter, a plurality of remote vibratory units corresponding in number with the hydraulic units and comprising pistons and cylinders, a pair of liquid conduits connecting the cylinder of each remote vibratory unit with the cylinder of a corresponding hydraulic unit, liquid columns in said conduits and cylinders, the liquid columns between the respective sides of the pistons of said cylinders being of substantially equal length.

3. A vibratory drive apparatus for the synchronous transmission of high frequency vibrations including a master high frequency pneumatic vibrator having a cylinder and piston, a plurality of hydraulic units comprising fixed cylinders and movable pistons, a drive bar connecting the master vibrator piston and all of the pistons of said units for simultaneously vibrating the latter, a plurality of remote vibratory units corresponding in number with the hydraulic units and comprising pistons and cylinders, a pair of liquid conduits connecting the cylinder of each remote vibratory unit with the cylinder of a corresponding hydraulic unit, liquid columns in said conduits and cylinders, the liquid columns between the respective sides of the pistons of said cylinders being of substantially equal length, a source of liquid supply under pressure, supply conduits connecting one conduit of each of said pairs of conduits with said source, a by-pass between each of said supply conduits and the other conduit of said pairs, and valves in the supply conduits on both sides of said by-passes whereby to compensate for volume changes in said liquid conduits.

THOMAS HUBBARD MORGAN.
